(57) **CLAIM**

The ornamental design for a three tiered tip for an earplug, a headphone or an earphone, as shown and described.

DESCRIPTION

FIG. 1 is a perspective view of a three tiered tip for an earplug, a headphone, or an earphone, showing the design; FIG. 2 is a side view of the three tiered tip for an earplug, a headphone, or an earphone of FIG. 1, wherein the tip is cylindrical and looks the same from each side;

FIG. 3 is a top view of the three tiered tip for an earplug, a headphone, or an earphone of FIG. 1; and,

FIG. 4 is a bottom view of the three tiered tip for an earplug, a headphone, or an earphone of FIG. 1.
